(57) **CLAIM**

The ornamental design for an instrument for treatment of soft tissue, as shown and described.

DESCRIPTION

FIG. 1 is a rear perspective view of an instrument for treatment of soft tissue, in accordance with the present invention;

FIG. 2 is a front view of the instrument for treatment of soft tissue of FIG. 1;

FIG. 3 is a left side view of the instrument for treatment of soft tissue of FIG. 1;

FIG. 4 is a right side view of the instrument for treatment of soft tissue of FIG. 3;

FIG. 5 is a top view of the instrument for treatment of soft tissue of FIG. 3;

FIG. 6 is a bottom view of the instrument for treatment of soft tissue of FIG. 1; and

FIG. 7 is a rear perspective view of the instrument for treatment of soft tissue of FIG. 1; and,

FIG. 8 is a front perspective view of the instrument for treatment of soft tissue of FIG. 1.
